UNITED STATES PATENT OFFICE.

PAUL HOFFMANN, OF CHARLOTTENBURG, GERMANY.

SPARK-DISCHARGING DEVICE FOR ELECTRIC LIGHTING FOR GAS-BURNERS.

SPECIFICATION forming part of Letters Patent No. 673,713, dated May 7, 1901.

Application filed March 24, 1900. Serial No. 10,076. (No model.)

To all whom it may concern:

Be it known that I, PAUL HOFFMANN, a subject of the Emperor of Germany, residing at Charlottenburg, near Berlin, in the Empire of Germany, have invented certain new and useful Improvements in and Connected with Spark-Discharging Devices for Electric Lighting for Gas-Burners, of which the following is a specification.

10 My invention relates to a device for lighting gas-light burners by means of an electric circuit from a distance, which device may be easily applied to or detached from any gas-burner.

15 In the accompanying drawings, Figure 1 shows a front view, and Fig. 2 a side view, of my new spark-discharging device attached to a gas-burner. Fig. 3 shows a side view of a modified form of the said device, and Fig. 4 represents the insulation of the spark-discharging device from the metal parts of the burner.

20 The said device consists of a small piece or stick of metal *a*, which may be made of sheet-iron, stiff wire, or the like. The said piece of metal *a* projects with its upper portion across the edge of the burner-head, while its lower portion, connected with the current-conducting wire *b*, is hooked under the burner-gallery. In the arrangement shown in Figs. 1 and 2 the metal piece or stick *a* itself is bent hook-like on its lower end in such a manner that a holdfast-hook *c* is formed on the same, by which the metal piece *a* is clamped or fixed to the bottom of the burner-gallery, thus effecting the attachment of the device to the burner without any further fastening means. Instead of being made in one piece with the stick *a* the holdfast-hook *c* may be fixed separately to the latter. Near the upper end the stick *a* may be provided with two side arms *d*, by means of which it leans against the burner-head. These two arms, however, may be dispensed with. The upper end of the piece *a*, which projects across the edge of the burner-head, is pointed in any well-known manner, and from this point of the piece *a* the sparks jump over to the opposite wire *k*, which is conductably connected to the burner-head. (See Fig. 4.) Hereby the lighting or ignition

of the gas escaping from the burner-head will be effected.

In the modification shown in Fig. 3 the metal piece *a* is provided with a special hook *g* of any ordinary kind, connected with the metal piece by means of a helical spring *f* and hooked under the burner-gallery. By means of the spring *f* the upper slightly-bent end of the stick *a* will be clamped or pressed against the edge of the burner-head, and thereby the device firmly fixed to the burner. As will be seen from the drawings, in both modes of construction the device can be easily applied to or detached from the burner-head. The necessary insulation of the spark-discharging device against the metal parts of the burner-head may be effected in any manner by interposing some insulating material—for instance, a small piece of mica. It proves very advantageous, too, to mount a cap *i* of soap-stone upon the burner-head, which permanently rests upon the latter, as shown in Fig. 4, thus effecting the insulation at the upper end of the spark-discharging device. The insulation at the lower end of the hook *c* will be effected, preferably, by an interposed layer *j* of any insulating material, which is to be fastened permanently within the hook *c* or at the respective portion of the burner-gallery.

25 Instead of lighting or igniting the gas by means of electric sparks it could be effected in another manner without leaving the nature of the above-described invention. For instance, the metal stick *a* may be provided at the top with a platinum wire, which is to be made incandescent by the electric current.

30 Having now described my invention, what I claim as new, and desire to secure by Letters Patent, is—

1. In a detachable spark-discharging device for electric lighting for gas-burners the combination of a metal piece or stick connected with the current-conducting line and projecting with its upper portion across the edge of the burner-head and a hook by means of which the device may be hooked under the burner-gallery, substantially as described.

2. In a detachable spark-discharging device for electric lighting for gas-burners, the combination of a metal piece or stick connected

with the current-conducting line and projecting with its upper portion across the edge of the burner-head and a holdfast-hook situated at the lower portion of the metal piece or stick 5 and stiffly connected with the latter, substantially as described and for the purpose set forth.

3. In combination with a burner, a current-conducting piece having its upper end over-
10 lapping the burner and its lower end provided

with an integral hook adapted to be sprung into engagement with the gallery, substantially as described.

In witness whereof I have hereunto set my hand in presence of two witnesses.

PAUL HOFFMANN.
